(57) **CLAIM**

The ornamental design for a magnetic hat clip, as shown and described.

DESCRIPTION

FIG. 1 is a front-top-left perspective view of a magnetic hat clip showing my new design, wherein the magnetic hat clip and a miniaturized flashlight in a deployed configuration;

FIG. 2 is a front-bottom-right perspective view thereof;

FIG. 3 is a front elevational view thereof;

FIG. 4 is a rear elevation view thereof;

FIG. 5 is a left elevational view thereof;

FIG. 6 is a right elevational view thereof;

FIG. 7 is a top plan view thereof;

FIG. 8 is a bottom plane view thereof;

FIG. 9 is a front-top-left perspective view of the magnetic hat clip, wherein the magnetic hat clip and the miniaturized flashlight in a collapsed configuration;

FIG. 10 is a front-bottom-right perspective view thereof;

FIG. 11 is a front-top-left perspective view of the magnetic hat clip, wherein the magnetic hat clip and the miniaturized flashlight in an exploded configuration;

FIG. 12 is a front-bottom-right perspective view thereof;

FIG. 13 is a supplemental perspective view of the magnetic hat clip attached to a baseball cap, wherein the magnetic hat clip and the miniaturized flashlight in a deployed configuration; and,

FIG. 14 is an enlarged detail view of the portion of the arms indicated in FIG. 4.

The broken lines showing a miniature flashlight, a set of arms, plate grooves, and a headwear in FIGS. 1 through 13 are included for the purpose of showing environmental structure and form no part of the claimed design.

1 Claim, 13 Drawing Sheets
